Claims priority, application Sweden September 25, 1952

3 Claims. (Cl. 274—9)

This invention relates to a phonograph device.

Since now phonograph records recorded at different speeds are marketed the phonographs have to be constructed to suit these different speeds. The speeds, which now are of current interest, are 78, 45 and 33½ R. P. M.

It is an object of this invention to produce a simple device to enable the phonographs to be regulated to the different speeds.

The invention will hereinafter be described with reference to the accompanying drawing.

In the drawing:

Fig. 1 is a plan view of a turntable, included in the device according to the invention.

Fig. 2 is a side view of this device.

In the drawing 1 designates a turntable, which is rotatably pivoted about a centering pin 2, which in turn is rotatably pivoted about a pin 3, arranged in a plane parallel to the plane of the turntable 1, and in a manner not shown is connected to a control device for the phonograph.

The mounting for the pin 3 consists of a clamp 4 fixed to the underside of the base plate 5. The turntable is near its periphery supplied with three rubber pads 6, against which the record rests during the reproduction. Furthermore three concentric ringshaped grooves are pressed down in the plane of the turntable near its periphery. These grooves form on the underside of the turntable ringshaped hills constituting three driving paths 7, 8 and 9 (corresponding to the speeds 33½, 45 and 78 R. P. M.) for an intermediate wheel 10, which extends through a recess in the base plate 5 of the phonograph and is rotatably pivoted about a shaft 11, arranged in a plane substantially perpendicular to the centering pin 2. This shaft 11 is through an arm 12 connected to a speed setting device (not shown) for the phonograph. By means of this device the intermediate wheel 10 is axially displaced to be brought before the driving paths 7, 8 and 9 respectively. In order to bring the intermediate wheel into engagement with these driving paths a spring 13 is arranged, which tends to press the arm 12 upwards against the base plate 5.

The intermediate wheel 10, which preferably has its driving rim of rubber, is further so arranged that it, in dependence of its axially displaced position is in engagement with one of three different sized driving wheels 14, 15 and 16 on a shaft 17 belonging to an electric motor 18, which is fastened to the base plate 5 of the phonograph. The engagement between the intermediate wheel 10 and the driving wheels 14, 15 and 16 is so chosen that it is diametrically opposite to the engagement between the intermediate wheel 10 and the driving paths 7, 8 and 9. The intermediate wheel 10 is thereby during the running of the phonograph fixed between its engagement spots which would not be the case, if as usual the angle between these spots is less than 180°. The arrangement of the intermediate wheel 10 such as it is used in the embodiment here described means great advantages with respect to the even rotational speed of the turntable.

2

The mode of operation of the above described device is as follows:

According to Figure 2 in the drawing the intermediate wheel 10 is in engagement with the driving path 9 of the turntable and with the driving wheel 16 of the shaft 17, whereby by running the motor the driving wheel 16 through the intermediate wheel 10 rotates the turntable at 78 R. P. M.

When the playing of a record is ended the centering pin 2 is given a clockwise rotation about its pivot 3 by means of a device (not shown) connected to the control device of the phonograph, thereby bringing the turntable away from the intermediate wheel 10, thus disengaging the turntable from this wheel. By influence of the spring 13 the arm 12 is brought upwards so that also the driving wheel 16 is disengaged from the intermediate wheel. This wheel will now be freely displaceable in its axial direction by means of the speed setting device of the phonograph.

If a turntable speed of 45 R. P. M. is desired the intermediate wheel 10 is by means of the last-mentioned device displaced to a position, where said wheel is situated above the driving wheel 15 of the shaft 17, after which movement the centering pin 2 is by the control device rotated anti-clockwise about its pivot 3. This means that the

turntable 1 with its driving path 8 is brought into engagement with the intermediate wheel 10 and presses this wheel to engagement with the driving wheel 15 of the shaft 17 against the action of the spring 13. In this position the centering pin 2 and thus the turntable 1 are held during the playing of a record by means of a spring not shown. By running the motor 18 the driving wheel 15 of the shaft 17 through the intermediate wheel 10 now rotates the turntable at 45 R. P. M.

If a turntable speed of 33½ R. P. M. is desired the intermediate wheel 10 is by means of the speed setting device displaced to a position, where said wheel is situated above the driving wheel 14 of the shaft 17, after which movement the intermediate wheel 10 is, in an analogous way as is described here above, brought into engagement with the driving path 7 of the turntable 1 and the driving wheel 14. By running the motor said wheel 14 through the intermediate wheel 10 now rotates the turntable at 33½ R. P. M.

In the embodiment described above the power transmission is constituted by an intermediate wheel 10 engaging on one hand the driving wheels 14, 15 and 16 respectively of the shaft 17 and on the other hand the driving paths 7, 8 and 9 respectively of the turntable 1. By this arrangement a double effect is obtained so that to have a desired turntable speed it is not necessary to displace the intermediate wheel so long a distance as the case would be if the intermediate wheel in its various axial positions engages a driving wheel with equal sized diameter and if thereby the different speeds of the turntable are obtained only by engaging the intermediate wheel with the turntable in different distances from its rotational centre. However this is possible without departing from the scope of invention.

The invention has here been described in connection with a single record player. Of course it is also possible to use it for a record changer.

Various modifications of the devices described above are of course possible within the scope of the appended claims.

65 What I claim is:

1. A phonograph comprising a turntable for supporting horizontally a record during its reproduction, a centering pin for passing through the center hole of the record, concentric ring-shaped projections beneath and near the periphery of the turntable to form a plurality of driving paths of different diameters, a base plate beneath the turntable and pivotally supporting the centering pin and

turntable, a motor fastened to the base plate and having its shaft extending in a plane substantially parallel to the plane of the turntable, a plurality of driving wheels of different sizes mounted longitudinally on said shaft and in vertical alignment with the concentric rings respectively, a vertically arranged intermediary wheel passing through a recess in the base plate and is laterally displaceable along said shaft to be brought in operative relationship with any one of said driving wheels and with the corresponding ring-shaped projection of the turntable, whereby the turntable may be rotated at different speeds suitable for different types of records and whereby the turntable and pivotal centering pin may be tilted to disengage the turntable from the intermediary wheel.

2. A phonograph as set forth in claim 1, wherein the point of engagement of the motor shaft with the inter-

10
mediary wheel is spaced about 180° from the point of contact of the intermediary wheel with the turntable whereby an even run of the turntable and a corresponding improved sound reproduction of the record is obtained.

3. A phonograph as set forth in claim 1, wherein said intermediary wheel is rotatably mounted on a shaft, the axis of which is perpendicular to the centering pin, and spring means for resiliently urging the intermediary wheel with any one of the driving paths of the turntable.
